UNITED STATES PATENT OFFICE.

THOMAS E. WADE, OF BURLINGAME, CALIFORNIA.

AIRSHIP.

1,303,999.

Specification of Letters Patent.

Patented May 20, 1919.

Application filed June 25, 1917. Serial No. 176,735.

To all whom it may concern:

Be it known that I, THOMAS E. WADE, a citizen of the United States, residing at Burlingame, in the county of San Mateo and 5 State of California, have invented new and useful Improvements in Airships, of which the following is a specification.

The present invention relates to improvements in air ships, the object of the invention being to provide an air ship which will have great stability, and which cannot be easily turned about its longitudinal axis, but which when so turned, will still be capable of directed flight.

15 I have herein shown my improved air ship in the form of a hydro-plane, but it is to be understood that my invention is not limited thereto.

In the accompanying drawing, Figure 1 is 20 a side view of the air ship; Figs. 2 and 3 are end views thereof.

Referring to the drawing, 1 indicates an engine house having therein an internal combustion engine 2; a radiator 3 for the 25 engine extends in front of, and is rigidly secured to, the engine house. From the radiator extend forwardly a plurality, here shown as four, of longitudinal bars 4, spaced from each other, and from the engine house 30 likewise extend rearwardly spaced longitudinal bars 5. These bars 4 as likewise the bars 5 are connected with each other by transverse and vertical struts 6 and tied to each other by oblique tie-wires 7, to form hollow frames, 8, 9, which, with the engine house and radiator, constitute, as it were, the backbone of the machine. Centrally within the 35 front frame 8 and supported at suitable intervals, with bearings 10 therein, is a driving shaft 11, driven by the engine, and carrying at the forward end of the frame, a propeller 12. In the rear frame 9 is contained a long, narrow gasoline chamber 13, in the form of a tube.

40 Extending transversely from the front portion of the front frame 8 are the sustaining planes 14, supported by tie-wires 15 connected to the sustaining planes and also to a metallic wing support 16 erected 45 upon said front portion of the frame. Said sustaining planes are also supported by tie-wires 17 connected thereto and to the front portions of front pontoons 18. Pivotally secured to the front edges of the sus-

taining planes are the rear edges of transversely extending elevators 19.

From the bars 4 and 5 of the front and rear frames extend obliquely outward, in upward and downward directions making angles of 45° with the horizon, planes 20 which gradually increase in width from front to rear, and which I term stability planes since they greatly increase the stability of the air ship. These planes are made of any suitable material, and are secured at 65 their outer edges to bars 21, which bars are connected at intervals with the bars 4 and 5 by transversely extending struts 22, which are tied together by oblique tie-wires 23. The front pontoons 18 are spaced from, and 70 connected with, each other by transverse bars 24, and are secured to the front frame 8 by front and rear oblique supports 26, 27, and are also secured to the lower bars 21 by front and rear supports 28 and 29. The 75 rear portions of said stability planes extend rearwardly beyond the rear frame 9, their inner edges having a general direction obliquely outward and being secured to bars 31, their outer edges extending parallel 80 with the back bone of the machine and being secured to bars 32. The terminal portions of the bars 31 and 32, where they join each other, carry loops 33, through which extend oblique straining wires 23, which are also 85 connected respectively to the ends of the rearmost bars 22. Rear pontoons 35 are secured along the greater part of their length to the lower outer bars 32 of the extensions of the stability planes. Turn-buckles are provided for tightening or 90 slackening the straining wires 23.

Between the bars 31 at the inner edges of the rear portion of the stability planes is interposed a cabin 38 for passengers. At 95 the sides of said cabin are supported balancing planes 39. Between the rear portions of the oblique bars 32 at the inner edges of the upper and lower rear portions of the stability planes, on each side of the machine, 100 is secured the front end of a rudder plane 40, so that there are two of said rudders, one on each side of the machine.

The elevators and rudders are controlled in the usual manner by cables running to 105 the engine room or to the cabin, as may be desired. A gyroscope 41 for adding to the stability of the air ship may be placed in

the rear frame or back bone immediately to the rear of the engine room, if desired. Wires 42 for receiving wireless messages are secured to the ends of the upper stability planes.

I have found by actual trial that an air ship of the above form possesses great stability, and it will be observed that, even though the air ship should turn about its longitudinal axis to any extent, it will still offer a large area of resistance to the air, and will drop slowly to the ground.

Copies of this patent may be obtained for five cents each, by addressing the "Commissioner of Patents, Washington, D. C."

I claim:

In an air ship, a longitudinal frame, sustaining planes supported by the front portion of said frame, and stability planes extending transversely from said longitudinal frame and increasing in width therefrom to rear, the rear portions of the stability planes having inner edges diverging from each other and a passenger cabin contained between said inner edges.

THOMAS E. WADE.
